SUBSTITUTED TRIFLUOROMETHYLTHIO- AND
TRIFLUOROMETHOXYPHENYL SULFONYL-
UREAS

Benjamin Blank, Philadelphia, and James F. Kerwin, Broome, Pa., assignors to Smith Kline & French Laboratories, Philadelphia, Pa., a corporation of Pennsylvania

No Drawing. Filed Apr. 22, 1959, Ser. No. 807,998
9 Claims. (Cl. 260—553)

This invention relates to novel substituted trifluoromethylthio- and trifluoromethoxyphenyl sulfonyleureas having valuable pharmacological activity. Further this invention relates to novel trifluoromethylthio- and trifluoromethoxybenzenesulfonamides useful as intermediates.

Specifically, the substituted sulfonyleureas of this invention lower blood glucose levels and thus are useful as hypoglycemic agents. These compounds are particularly useful due to their activity upon oral administration. Further, the compounds of this invention are active over a prolonged period of time and are relatively free of side effects.

The novel substituted trifluoromethylthio- and trifluoromethoxyphenyl sulfonyleureas of this invention are represented by the following fundamental formula:

FORMULA I

when:

R₁ represents trifluoromethylthio or trifluoromethoxy; and

R₂ represents lower alkyl, lower cycloalkyl, lower alkoxy-alkylene or lower alkyl mercapto-alkylene.

The R₁ moiety is preferably in the para position of the benzene ring.

Advantageous compounds of this invention are represented by the following fundamental formula:

FORMULA II

when:

R₁ represents trifluoromethylthio or trifluoromethoxy; and

R₂ represents lower alkyl, preferably containing from 2 to 5 carbon atoms; lower cycloalkyl, preferably containing from 5 to 6 carbon atoms; lower alkoxy-alkylene, the lower alkoxy moiety preferably containing from 1 to 3 carbon atoms and the alkylene moiety preferably containing from 2 to 4 carbon atoms; or lower alkyl mercapto-alkylene, the lower alkyl mercapto moiety preferably containing from 1 to 3 carbon atoms and the alkylene moiety preferably containing from 2 to 4 carbon atoms.

Preferred compounds of this invention are represented by the following fundamental formula:

FORMULA III

when:

R₁ represents trifluoromethylthio or trifluoromethoxy; and

R₂ represents propyl, butyl, cyclohexyl, methoxyethyl, methoxypropyl, methylmercaptoethyl or methylmercapto-propyl.

Particularly preferred and advantageous compounds of this invention are represented by Formula III above when R₂ represents propyl or butyl.

2

When the term "lower alkyl" is used herein, aliphatic groups having not more than 6 carbon atoms are indicated except where otherwise specified. When the term "lower cycloalkyl" is used herein, cycloaliphatic groups having not more than 6 carbon atoms are indicated. When the term "lower alkoxy" is used herein, aliphatic groups having not more than 4 carbon atoms are indicated except where otherwise specified. When the term "alkylene" is used in connection with a carbon chain, aliphatic groups having not more than 6 carbon atoms are indicated except where otherwise specified. When the term "lower alkyl mercapto" is used herein, aliphatic groups having not more than 4 carbon atoms are indicated except where otherwise specified. The aliphatic groups herein defined may be straight or branched chain.

The novel trifluoromethylthio- and trifluoromethoxybenzenesulfonamides of this invention useful as intermediates in the preparation of the sulfonyleureas described in Formula I above, as is outlined more fully hereinafter, are represented by the following formula:

FORMULA IV

when:

R₁ represents trifluoromethylthio or trifluoromethoxy.

The R₁ moiety is preferably in the para position of the benzene ring.

30 The sulfonamides of Formula IV are advantageously prepared from the corresponding trifluoromethylthio- and trifluoromethoxy substituted benzene derivatives. Thus, a solution of the appropriate substituted benzene derivative in an unreactive organic solvent, for example chloroform or carbon tetrachloride, is reacted with an excess (at least two equivalents) of chlorosulfonic acid at a temperature in the range of from 0 to 30° C. for from two to six hours. The reaction mixture is then treated with ice and water to decompose the excess chlorosulfonic acid and the resultant organic phase containing the substituted benzenesulfonyl chloride is evaporated to dryness with ammonium carbonate. The residue is water-washed to give the corresponding trifluoromethylthio- or trifluoromethoxybenzenesulfonamides which are then further reacted as described hereinafter to prepare the sulfonyleurea products of this invention.

40 Alternatively, the above substituted benzene sulfonyl chlorides are prepared from the corresponding sulfonic acid by reaction with phosphorus pentachloride or phosphorus oxychloride. Also, the sulfonyl chlorides are converted to the sulfonamides by reaction with aqueous ammonia.

50 An advantageous method of preparation of the novel trifluoromethylthio- and trifluoromethoxyphenyl sulfonyleurea derivatives of this invention comprises the reaction of the appropriate substituted benzenesulfonamide with an isocyanate, illustrated as follows:

in which R₁ and R₂ are as defined above. In this method,

65 the isocyanate is reacted with a stirred solution of the sulfonamide dissolved in one equivalent of an alkali metal hydroxide such as sodium hydroxide, containing a volume of an unreactive organic solvent such as acetone, sufficient to maintain a homogeneous solution, at a temperature in the range of from 0 to 60° C. for from one to eight hours. The product is obtained by removing the organic solvent and acidifying the residue with a dilute

acid such as a mineral acid, for example hydrochloric acid, or a weak organic acid, for example acetic acid. The solid is removed by filtration and purified by recrystallization. This method is especially advantageous when the appropriate isocyanate is readily available.

Following the method outlined above, the sulfonylurea products wherein R_2 of Formula I is lower alkoxyalkylene or lower alkyl mercapto-alkylene are also advantageously prepared by first reacting the sulfonamide with an isocyanate containing a reactive alkyl ester moiety for example a haloalkyl moiety, preferably chloroalkyl, and the thus formed haloalkyl urea derivative is further reacted with an appropriate alcohol or mercaptan so as to yield the said sulfonylurea products. The alkali metal salt, preferably sodium, of the alcohol or mercaptan is used in the above method and the reaction is run in an unreactive organic solvent such as ethanol or isopropanol, at reflux temperature for from two to six hours. The reaction mixture is filtered and acidified to give the product upon cooling.

Alternatively, the sulfonylureas of this invention are prepared by the reaction of trifluoromethylthio- or trifluoromethoxyphenylsulfonyl isocyanate (obtained by standard procedures such as for example by the reaction of trifluoromethylthio- or trifluoromethoxybenzenesulfonamide with phosgene) with a primary amine containing the R_2 moiety as defined in Formula I, outlined as follows:

In this method, the isocyanate is reacted with a stirred solution of the amine dissolved in an unreactive organic solvent such as for example benzene or dioxane, at a temperature in the range of from 0 to 60° C. for from one to eight hours. The product is isolated by cooling and filtering, and is purified by recrystallization.

Further, the sulfonylureas of this invention are prepared by other methods useful in urea syntheses. For example, trifluoromethylthio- or trifluoromethoxyphenylsulfonylurea (prepared by standard methods such as for example by the reaction of trifluoromethylthio- or trifluoromethoxybenzenesulfonamide with potassium cyanate) is reacted with R_2-NH_2 to yield the desired product. Also, trifluoromethylthio- or trifluoromethoxybenzenesulfonamide is reacted with ethyl chlorocarbonate to give the corresponding N-carboxy-sulfonamide derivative which is in turn reacted with R_2-NH_2 to yield the sulfonylurea products.

It will be obvious to one skilled in the art that other methods are adaptable for the preparation of the sulfonylureas of this invention. The foregoing is a general description of several advantageous methods. Of particular advantage as a preparative method is the reaction of trifluoromethylthio- or trifluoromethoxybenzenesulfonamide with R_2-NCO , R_2 being defined as in Formula I.

The following examples illustrate the compounds of this invention and the procedures for their preparation, but are not to be construed as limiting the invention except within the definition of the fundamental Formula I given above.

Example 1

To a stirred solution of 53.4 g. of trifluoromethylthiophenol in 150 ml. of chloroform cooled to 5° C. is added 186.0 g. of chlorosulfonic acid, the temperature maintained below 10° C. After addition is complete, the mixture is stirred with cooling for one hour and then at room temperature for an additional two hours. The mixture is added dropwise to a stirred mixture of ice and water. The layers are separated and the aqueous

layer is extracted with chloroform. The combined chloroform solution is dried and evaporated to dryness with 100.0 g. of ammonium carbonate. The residue is suspended in water, filtered, and washed with water to give the product, p-trifluoromethylthiobenzenesulfonamide. Recrystallization from 50% aqueous ethanol yields pure crystals melting at 160-162° C.

Example 2

10 To a stirred solution of 12.0 g. of trifluoromethoxybenzene in 40 ml. of chloroform cooled to 0-5° C. is added 46.0 g. of chlorosulfonic acid at such a rate that the temperature does not exceed 10° C. The solution is stirred one hour with cooling during which time hydrogen chloride is vigorously evolved. The reaction mixture is stirred an additional two hours at room temperature and is then added dropwise to a stirred mixture of ice and water. The layers are separated and the aqueous layer is extracted with chloroform. The chloroform phases are combined, dried over magnesium sulfate, and evaporated to dryness with 25.0 g. of ammonium carbonate. The residue is suspended in water, filtered, and washed with water. The solid is recrystallized from toluene to give p-trifluoromethoxybenzenesulfonamide, M.P. 144-145° C.

Example 3

30 To a solution of 2.6 g. of p-trifluoromethylthiobenzenesulfonamide in 10 ml. of 1 N sodium hydroxide and 10 ml. of acetone cooled to 0-5° C. is added dropwise a solution of 1.1 g. of n-butyl isocyanate in 5 ml. of acetone, the temperature maintained below 10° C. during the addition. The resulting mixture is stirred one hour with cooling and then two hours at room temperature. The acetone is removed at reduced pressure at a bath temperature of about 40° C. and the aqueous residue is acidified with dilute hydrochloric acid with cooling. The solid is filtered, washed with water, and recrystallized from aqueous methanol to give (N¹-p-trifluoromethylthiophenylsulfonyl-N³-n-butyl)-urea, M.P. 119-120° C.

Example 4

45 A solution of 2.3 g. of n-propyl isocyanate in 10 ml. of acetone is added dropwise to a solution of 6.4 g. of p-trifluoromethylthiobenzenesulfonamide in 25 ml. of 1 N sodium hydroxide and 25 ml. of acetone at 0-5° C. The mixture is stirred one hour with cooling and then two hours at room temperature. The acetone is removed in vacuo and the residue acidified with dilute hydrochloric acid to give the product (N¹-p-trifluoromethylthiophenylsulfonyl-N³-n-propyl)urea, M.P. 137-138.5° C.

Example 5

55 To a solution of 4.8 g. of p-trifluoromethoxybenzenesulfonamide in 20 ml. of 1 N sodium hydroxide and 20 ml. of acetone cooled to 0-5° C. is added dropwise a solution of 2.2 g. of n-butyl isocyanate in 10 ml. of acetone, maintaining the temperature below 10° C. during the addition. The mixture is then stirred one hour with cooling and two hours at room temperature. The acetone is removed in vacuo and the residue is acidified with dilute hydrochloric acid. The solid is filtered, washed with water, and recrystallized from aqueous methanol to yield (N¹-p-trifluoromethoxyphenylsulfonyl-N³-n-butyl)urea, M.P. 107-109° C.

Example 6

70 A solution of 2.8 g. of n-propyl isocyanate in 10 ml. of acetone is added dropwise to a solution of 7.2 g. of p-trifluoromethoxybenzenesulfonamide in 30 ml. of 1 N sodium hydroxide and 30 ml. of acetone at 0-5° C. The mixture is stirred one hour with cooling and then two hours at room temperature. The acetone is removed in vacuo and the residue acidified with dilute hydrochloric acid to give (N¹-p-trifluoromethoxyphenylsulfonyl-N³-n-propyl)urea, M.P. 123-124° C.

Example 7

A solution of 31.0 g. of p-trifluoromethylthiophenylsulfonyl isocyanate (prepared from the reaction of 35.0 g. of p-trifluoromethylthiobenzenesulfonamide with an excess of phosgene and heating the carbamyl chloride thus formed) in 125 ml. of benzene is added in portions to a solution of 9.9 g. of cyclohexylamine in 100 ml. of benzene. The solution is stirred for six hours at 40-50° C. To the cooled reaction mixture, 300 ml. of ether is added and the solid which separates is filtered and recrystallized to give (N¹-p-trifluoromethylthiophenylsulfonyl-N³-cyclohexyl)urea.

Similarly, following the above procedure, 15.5 g. of p-trifluoromethylthiophenylsulfonyl isocyanate and 4.3 g. of cyclopentylamine are reacted to yield (N¹-p-trifluoromethylthiophenylsulfonyl-N³-cyclopentyl)urea.

Example 8

A mixture of 3.0 g. of 2-methoxyethylamine and 2.8 g. of p-trifluoromethoxyphenylsulfonylurea (prepared from the reaction of 3.2 g. of p-trifluoromethoxybenzenesulfonamide with potassium isocyanate) in 20 ml. of glacial acetic acid is heated at 95° C. with stirring for one hour. The reaction mixture is cooled and then diluted with 100 ml. of water. The solid which precipitates is removed by filtration, washed with water and recrystallized to give [N¹-(p-trifluoromethoxyphenylsulfonyl)-N³-(2-methoxyethyl)]-urea.

Example 9

A solution of 8.8 g. of p-trifluoromethoxyphenylsulfonyl isocyanate (prepared from the reaction of 11.0 g. of p-trifluoromethoxybenzenesulfonamide with an excess of phosgene and heating the carbamyl chloride thus formed) in 50 ml. of benzene is added in portions to a solution of 3.0 g. of cyclohexylamine in 50 ml. of benzene. The solution is stirred for six hours at 40-50° C. and worked up as described in Example 7 to yield (N¹-p-trifluoromethoxyphenylsulfonyl-N³-cyclohexyl)urea.

Example 10

To a solution of 25.7 g. of p-trifluoromethylthiobenzenesulfonamide in 125 ml. of 1 N sodium hydroxide and 200 ml. of acetone is added dropwise with stirring and cooling a solution of 12.1 g. of 2-chloroethylisocyanate in 100 ml. of acetone. The reaction mixture is then stirred for an additional two hours. The acetone is removed and the residue is acidified with aqueous acetic acid. The solid is filtered and recrystallized to give [N¹-(p-trifluoromethylthiophenylsulfonyl)-N³-(2-chloroethyl)]urea.

A mixture of 37.2 g. of the 2-chloroethyl urea prepared above, 4.6 g. of sodium and 16.0 g. of methylmercaptan in 300 ml. of ethanol is refluxed for three hours. The reaction mixture is cooled, diluted with water and filtered. The filtrate is acidified with acetic acid and cooled to precipitate the product, [N¹-(p-trifluoromethylthiophenylsulfonyl)-N³-(2-methylmercaptoethyl)]urea.

Example 11

A solution of 29.8 g. of p-trifluoromethoxyphenylsulfonyl isocyanate in 250 ml. of benzene is added dropwise to a solution of 10.5 g. of 3-methylmercaptopropylamine in 100 ml. of benzene. The resulting mixture is stirred for six hours at 60° C., cooled and diluted with 250 ml. of ether to precipitate the solid product, [N¹-(p-trifluoromethoxyphenylsulfonyl)-N³-(3-methylmercaptopropyl)]urea.

Similarly, following the above procedure, 29.8 g. of p-trifluoromethoxyphenylsulfonyl isocyanate is reacted with 11.9 g. of 2-propylmercaptopropylamine or 11.9 g. of 3-ethylmercaptopropylamine to yield [N¹-(p-trifluoromethoxyphenylsulfonyl)-N³-(2-propylmercaptopropyl)]urea and [N¹-(p-trifluoromethoxyphenylsulfonyl)-N³-(3-ethylmercaptopropyl)]urea, respectively.

Example 12

To a solution of 2.6 g. of p-trifluoromethylthiobenzenesulfonamide in 10 ml. of 1 N sodium hydroxide and 10 ml. of acetone is added a solution of 0.8 g. of ethyl isocyanate in 10 ml. of acetone. The isocyanate is added dropwise with stirring and at a temperature of 5-10° C. The reaction mixture after addition is stirred at room temperature for two hours and then the acetone is removed. Acidification of the residue with dilute hydrochloric acid yields the product, (N¹-p-trifluoromethylthiophenylsulfonyl-N³-ethyl)urea.

Example 13

A solution of 3.0 g. of p-trifluoromethoxyphenylsulfonyl isocyanate in 30 ml. of benzene is added dropwise to a solution of 1.0 g. of n-hexylamine in 20 ml. of benzene. The resulting solution is stirred for eight hours at 60° C., cooled and diluted with ether to yield (N¹-p-trifluoromethoxyphenylsulfonyl-N³-n-hexyl)urea.

Example 14

A solution of 2.5 g. of 3-methoxypropyl isocyanate in 10 ml. of acetone is added dropwise with stirring to a solution of 5.1 g. of p-trifluoromethylthiobenzenesulfonamide in 20 ml. of 1 N sodium hydroxide and 20 ml. of acetone at 5-10° C. The mixture is stirred for four hours at 40-50° C., cooled and the acetone removed. The residue is acidified with dilute hydrochloric acid to yield [N¹-(p-trifluoromethylthiophenylsulfonyl)-N³-(3-methoxypropyl)]urea.

Similarly, following the above procedure, 3.1 g. of 2-butoxyethyl isocyanate and 5.1 g. of p-trifluoromethylthiobenzenesulfonamide are reacted to give [N¹-(p-trifluoromethylthiophenylsulfonyl)-N³-(2-butoxyethyl)]urea.

Example 15

A mixture of 3.7 g. of [N¹-(p-trifluoromethylthiophenylsulfonyl)-N³-(2-chloroethyl)]urea (prepared as in Example 10) and 1.6 g. of sodium isopropoxide in 100 ml. of isopropanol is heated at reflux for four hours. The reaction mixture is cooled, diluted with water and filtered. Acidification of the filtrate with acetic acid and cooling yields the product, [N¹-(p-trifluoromethylthiophenylsulfonyl)-N³-(2-isopropoxyethyl)]urea.

Example 16

To a solution of 11.9 g. of 4-methylmercaptopropylamine in 100 ml. of benzene is added a solution of 31.2 g. of p-trifluoromethylthiophenylsulfonyl isocyanate in 250 ml. of benzene, dropwise with stirring. The solution is stirred for six hours at 60° C., cooled and diluted with ether. The resultant solid is filtered and recrystallized to give [N¹-(p-trifluoromethylthiophenylsulfonyl)-N³-(4-methylmercaptopropyl)]urea.

Similarly, following the above procedure, 13.1 g. of 6-methoxyhexylamine and 29.4 g. of p-trifluoromethoxyphenylsulfonyl isocyanate are reacted to yield [N¹-(p-trifluoromethoxyphenylsulfonyl)-N³-(6-methoxyhexyl)]urea.

Example 17

A solution of 29.4 g. of p-trifluoromethoxyphenylsulfonyl isocyanate in 250 ml. of benzene is added dropwise with stirring to a solution of 10.3 g. of 3-methoxyisobutylamine in 150 ml. of benzene. The resulting solution is stirred for an additional six hours at 50-60° C., cooled and diluted with ether. The solid which separates is removed and purified by recrystallization to give [N¹-(p-trifluoromethoxyphenylsulfonyl)-N³-(3-methoxyisobutyl)]urea.

Example 18

A solution of 7.3 g. of p-trifluoromethoxyphenylsulfonyl isocyanate in 100 ml. of benzene is added dropwise with stirring to a solution of 1.5 g. of isopropylamine in 50

ml. of benzene at a temperature of 20-30° C. The solution is stirred for two hours and then diluted with ether to yield (N¹-p-trifluoromethoxyphenylsulfonyl-N³-isopropyl)-urea.

Example 19

A solution of 15.5 g. of p-trifluoromethylthiophenylsulfonyl isocyanate in 200 ml. of benzene is added dropwise to a stirred solution of 6.7 g. of 2-butymercaptopethylamine in 100 ml. of benzene. The solution is stirred for six hours at 50-60° C., cooled and diluted with ether. The resultant solid is purified by recrystallization to give [N¹ - (p-trifluoromethylthiophenylsulfonyl) - N³ - (2-butymercaptopethyl)]urea.

Similarly, following the above procedure, 14.7 g. of p-trifluoromethoxyphenylsulfonyl isocyanate is reacted with 5.9 g. of 4-ethoxybutylamine to give [N¹-(p-trifluoromethoxyphenylsulfonyl)-N³-(4-ethoxybutyl)]urea.

What is claimed is:

1. A chemical compound having the following formula:

in which R₁ is a member selected from the group consisting of trifluoromethylthio and trifluoromethoxy; and R₂ is a member selected from the group consisting of lower alkyl of from 2 to 5 carbon atoms; lower cycloalkyl of from 5 to 6 carbon atoms; lower alkoxyalkylene, the lower alkoxy moiety is from 1 to 3 carbon atoms and the alkylene moiety is of from 2 to 4 carbon atoms; and lower alkyl mercapto-alkylene, the lower alkyl mercapto moiety is of from 1 to 3 carbon atoms and the alkylene moiety is of from 2 to 4 carbon atoms.

2. A chemical compound having the following formula:

in which R₁ is a member selected from the group consisting of trifluoromethylthio and trifluoromethoxy.

3. A chemical compound having the following formula:

4. A chemical compound having the following formula:

5. A chemical compound having the following formula:

6. A chemical compound having the following formula:

7. A chemical compound having the following formula:

8. A chemical compound having the following formula:

25 9. A chemical compound having the following formula:
